Primary Examiner — Robert M Spear

Assistant Examiner — Darcey E Heflin

(74) Attorney, Agent, or Firm — Irina Hass

(57) **CLAIM**

The ornamental design for a combined container and tool, as shown and described.

DESCRIPTION

FIG. 1 is a perspective view of a combined container and tool showing the new design;

FIG. 2 is a front view thereof;

FIG. 3 is a rear view thereof;

FIG. 4 is a right side view thereof, a left side view being a mirror image thereof;

FIG. 5 is a top view thereof; and,

FIG. 6 is a bottom view thereof.

The portions of the combined container and tool in FIGS. 1-4 and 6 shown in evenly-spaced broken lines are included to show features that form no part of the claimed design.

1 Claim, 2 Drawing Sheets(56)
